UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

REFLECTOR-SHADE FOR LAMPS.

1,186,165.

Specification of Letters Patent. Patented June 6, 1916.

Application filed October 10, 1913. Serial No. 794,489.

To all whom it may concern:

Be it known that I, REUBEN B. BENJAMIN, a citizen of the United States, residing at Chicago, in the county of Cook and State 5 of Illinois, have invented new and useful Improvements in Reflector-Shades for Lamps, of which the following is a full, clear, concise, and exact description, reference being had to the accompanying drawing, forming a part of this specification.

My invention pertains to reflector shades for lamps, and particularly to reflector shades of the bowl type.

Reflector shades, and especially bowl shades, as heretofore known, have been subject to the disadvantage that a large percentage of the light rays emanating from the lamp filament are reflected back along paths that pass through the lamp bulb. In 15 thus passing through two thicknesses of glass, much of the reflected light is absorbed, the efficiency of the shade being thus lessened. The loss is particularly noticeable in the case of bowl-frosted lamp bulbs.

It is the principal object of my invention to obviate this disadvantage, and to provide a reflector shade of a higher efficiency than has heretofore been produced. This object is attained by forming portions of the reflecting surface of the shade in such a manner that the light rays incident thereon will be reflected out through the space which exists between the lamp bulb and the inner surface of the shade.

A reflector shade embodying my invention is described, by way of example, in the following specification, and shown in the accompanying drawings, in which:

Figure 1 is a vertical section through the 40 reflector shade, a lamp socket and lamp being shown in position therein; Figs. 2-8 are fragmentary sectional views, showing the arrangement of the radial corrugations of the shade, the sections being taken, respectively, on the lines O²-O⁸ of Fig. 1; Fig. 9 is a view similar to a portion of Fig. 1, illustrating the manner in which the rays are reflected vertically; Figs. 10 and 11 are sectional views taken, respectively, on the lines 45 10-10 and 11-11 of Fig. 9, looking in the direction of the arrows, and illustrating the manner in which the rays indicated in Fig. 9 are reflected laterally; and Fig. 12 is a horizontal section taken on the line 12-12

of Fig. 1, looking in the direction of the 55 arrows.

The reflector shade embodying my invention now to be described, has a bowl portion 13 and a casing portion 14, the latter being adapted to inclose and contain the lamp 60 socket 15 and the reduced upper end of the lamp 16. In the top of the casing portion 14 is an aperture in which is arranged a bushing 17 adapted to receive a conduit or the like. The lower end of the bushing 17 65 is screw-threaded on the exterior to engage the interior screw-threads of a stirrup 18 which is disposed within the casing 14 and secured to the socket 15 by screws 19. Between the casing portion 14 and the bushing 70 17 and the flange 20 and stirrup 18, respectively, are placed a pair of washers 22 and 23. In the casing 14 just above the bowl portion are a plurality of ventilating apertures 25.

The bowl portion 13 of the shade is fluted or corrugated, the corrugations 26 having the form and angularity shown in the drawings by Figs. 1-8. These corrugations 26 are radial and as the shade widens out the corrugations uniformly diminish. That is, at a point near the top of the shade the degree of corrugation is greatest, and near the bottom of the shade the corrugations merge into a spherical surface. To be more specific, 80 reference is made to Figs. 2-8 taken in connection with Fig. 1. Considering the point A (Fig. 1) as a center, it will be seen that at a point 30° removed from the axis of the shade, that is, almost at the top of the bowl, 90 the shade is plain and unfluted, (Fig. 2). At a point 40° removed the corrugation in the shade has an angle of 125° (Fig. 3) and at the 60° point the angle is 136° (Fig. 4). Continuing in this manner it will be apparent from the figures of the drawings above referred to, that the angle of the corrugations increases, uniformly toward the bottom of the shade until at a point 100° from the axis, the corrugations merge into a 100 spherical surface (Fig. 8). At its lower part, the bowl portion 13 is formed with a flaring hood portion 24.

The result of forming the shade as described above is that the great majority of 105 the reflected rays are projected downwardly and outwardly through the space between the shade and the lamp bulb; so that there

- is little impairment of efficiency due to loss of light by absorption in passing through the lamp bulb. It has been noted that as the bowl portion 13 widens out the degree of 5 corrugation diminishes, so that the above effect obtains throughout the entire depth of the bowl portion. Figs. 9-11 show this clearly, the two rays there shown being taken at random as examples. For the purposes of description, it is assumed that the light rays emanate from a single point A, at the center of the filament. Considering Fig. 9, which shows the vertical paths traversed by the rays, AD represents a ray striking the shade at the point D, and DF represents the corresponding reflected ray. AE represents another ray incident at E and reflected along EG. Fig. 9 shows the paths of the rays AD, 20 DF and AE, EG, considered vertically. Figs. 10 and 11 show the same rays considered laterally, the sections on which these figures are taken being on the same planes as the rays DF and EG, respectively. That 25 is, Fig. 9 shows the rays projected downwardly and Figs. 10 and 11 illustrate the paths along which the rays are reflected outwardly, the latter figures clearly showing that such paths pass through the space between the shade and the side of the lamp. It 30 is seen, therefore, that by virtue of the corrugations and their arrangement, the angle of incidence of substantially every ray striking the shade is such that the corresponding reflected ray passes downwardly and outwardly through the space existing between the shade and the lamp. Loss by absorption, due to the passage of rays through the lamp bulb, is thus avoided. 35 40 Not only does my invention make possible a shade of greater efficiency than heretofore known, by doing away with loss due to absorption, but in addition a shade so constructed possesses ornamental features, and, 45 furthermore, the corrugations provide an additional element of strength in the shade. Having thus described my invention, what I claim as new and desire to secure by Letters Patent is:
- 50 1. A bowl shaped reflector shade comprising angularly disposed portions each curv-

ing downwardly and gradually enlarging so as to project the rays incident thereon downwardly and sidewise to avoid the bulb and shade. 55

2. A bowl shaped reflector shade for lamps comprising radial corrugations with angularly disposed sides whose angular relations gradually increase so as to merge into a substantially circular surface at the 60 lower end of the shade, said sides also curving vertically so as to project the rays of light incident thereon downwardly and sidewise between the bulb and shade. 65

3. A reflector shade for lamps having a portion of its surface substantially perpendicular to a line bisecting the angle between a line from the source of light to a point in said surface, and a line from said point extending between the side of the lamp and the 70 shade, and also extending outside of the plane through said point and the axis of the lamp. 75

4. A reflector shade for lamps having a bowl shaped radially corrugated surface 80 having portions each of which is substantially perpendicular to a line bisecting the angle between a line from the source of light to a point in said surface, and a line from said point extending between the side of the lamp and the shade, and also extending outside of the plane through said point and the axis of the lamp. 85

5. A reflector shade for lamps having a bowl shaped radially corrugated surface 90 having portions each of which is substantially perpendicular to a line bisecting the angle between a line from the source of light to a point in said surface, and a line from said point extending between the side of the lamp and the shade, and also extending outside of the plane through said point and the axis of the lamp, the acuteness of the angle between the sides of said corrugations decreasing outwardly. 95

In witness whereof, I have hereunto subscribed my name in the presence of two witnesses.

REUBEN B. BENJAMIN.
